UNITED STATES PATENT OFFICE.

ALBERT HAZEN SARGENT, OF BANGOR, MAINE.

HEATER FOR AUTOMOBILE ENGINES.

Application filed April 9, 1927. Serial No. 182,451.

This invention relates to improvements in heaters, particularly in connection with automobile engines.

A prime object of this invention is to provide a heater, simple of construction and easily applied to the desired part of an automobile engine, in order to keep the motor warm and easy to start, particularly in cold weather, the register of the heater being adapted to be placed approximately under the base of the engine in the center.

Other objects of this invention will appear from the following detailed description of the device and as disclosed in the single sheet of drawings herewith made a part of this application.

In the drawings—

Figure 1 represents a perspective view of the heating device with its different elements in assembled relationship.

Figure 2 illustrates a vertical sectional view of the heater.

Figure 3 represents a sectional view on line 3—3 of Figure 2 on an enlarged scale, of the main end of the heater.

Figure 4 represents a sectional view of the heater taken along line 4—4 of Figure 2.

Numeral 1 designates the main portion of the heating device which may be termed a burner box, adapted to receive therein a gas burner 2 or other suitable source of heat, the gas entering the burner 2 in this instance through a fitting 3 connected to the source 35 of fuel or gas supply. The container or burner box 1 may be made of any suitable material, such as sheet metal, and is adapted to be connected in open communication with a register box 4 by means of a suitable pipe 40 element 5. The opening 6 in the burner box 1 for receiving one end of the pipe element 5 is preferably located near the lower edge of one side wall; the opening 7 in the register box 4 for receiving the opposite end of 45 the pipe element 5 is located near the upper edge of one of the sides, thereby forming a heating device in which the heat generated from the gas connection 2 or other source will flow slightly upwardly through the pipe 50 element 5 into the register box 4 and thence from the opening 8 in the upper portion of the register box 4, to the operating part of the engine, which it is desired to keep warm for easily starting in cold weather. The 55 pipe element 5 may be made of any suitable material, such as sheet metal, and consists of

sections adapted to be telescopically connected together as at 9 and 10 in order to allow for increase or decrease in length of the pipe element 5. The burner box 1, register box 4 and pipe element 5 may be connected together in any practical manner, such as by soldering or preferably by flange portions as disclosed in the drawings at 11, and 12, the flanges being properly riveted 65 to the cooperating sides of the box elements.

In order to increase the heating efficiency, and eliminate, as far as possible, the loss of heat, an insulation 13, such as asbestos, may be placed around the pipe element 5 and 70 clamped in position by means of elements 14, 15 and 16.

In the construction of the burner box 1 it is preferred to provide an opening 17 which is adapted to be covered as at 18 75 with a fine mesh removable wire cloth, preferably brass cloth. This fine mesh cloth may be located at any suitable point near the top of the burner box 1 and the opening 17 thereof. The heater box 1 may also be 80 provided with a removable cover portion 19 allowing, however, at all times, a sufficient air circulation for the purpose of the proper burning of the gas jet or other source of heat within the box 1.

This invention provides a simple and inexpensive heater adapted for the purpose of keeping operating parts of engines on motor cars warm and easy to start in cold weather. The register 90 box 4 is placed under the base of the engine, preferably near the center thereof, and it is apparent that the heat from the burner box which will circulate through the heating device and function to produce the heat required for warming the 95 operating parts of the motor.

What I claim is:

1. A heater for maintaining the operating parts of engines on motor cars warm and easy to start in cold weather, consisting of 100 a burner box provided with heating means, a register box, and a pipe element arranged in open communication between the burner box and register box.

2. A heater for maintaining the operating parts of engines on motor cars warm and easy to start in cold weather, consisting of 105 a burner box provided with heating means, a register box, and a pipe element arranged in open communication between the burner 110 box and register box, the pipe element being arranged to enter the burner box near

the bottom thereof and the register box near the top edge thereof, thereby providing an upward flow chamber for the heat between the two boxes.

5. A heater for maintaining the operating parts of engines on motor cars warm and easy to start in cold weather, consisting of a burner box provided with heating means, a register box, and a pipe element arranged in open communication between the burner box and register box, the pipe element being arranged to enter the burner box near the bottom thereof and the register box near the top edge thereof, thereby providing an upward flow chamber for the heat between the two boxes, both the burner box and the register box having an opening in the upper portion thereof.

6. A heater for maintaining the operating parts of engines on motor cars warm and easy to start in cold weather, consisting of a burner box provided with heating means, a register box, and a pipe element arranged in open communication between the burner box and register box, the pipe element being arranged to enter the burner box near the bottom thereof and the register box near the top edge thereof, thereby providing an

upward flow chamber for the heat between the two boxes, both the burner box and the register box having an opening in the upper portion thereof, the opening in the burner box being adapted to be covered by a suitable fine mesh wire. 30

5. A heater for maintaining the operating parts of engines on motor cars warm and easy to start in cold weather, consisting of a burner box provided with heating means, a register box, and a pipe element arranged in open communication between the burner box and register box, the pipe element being arranged to enter the burner box near the bottom thereof and the register box near the top edge thereof, thereby providing an upward flow chamber for the heat between the two boxes, both the burner box and the register box having an opening in the upper portion thereof, the opening in the burner box being adapted to be covered by a suitable fine mesh wire, the pipe element consisting of sections telescopically arranged for the purpose of adjusting the length and insulating material surrounding the pipe. 40

50 In testimony whereof I affix my signature.

ALBERT HAZEN SARGENT.
